UNITED STATES PATENT OFFICE

133,097

DESIGN FOR A DRAFTING IMPLEMENT

Joseph I. Carr, Annapolis, Md.

Application April 2, 1942, Serial No. 106,441

Term of patent 14 years

To all whom it may concern:

Be it known that I, Joseph I. Carr, a citizen of the United States, residing at Annapolis, in the county of Anne Arundel and State of Maryland, have invented a new, original, and ornamental Design for a Drafting Implement, of which the following is a specification, reference being had to the accompanying drawing, forming part thereof.

Figure 1 is a top plan view of a drafting implement showing my new design.

Figure 2 is an edge elevational view.

Figure 3 is an end elevational view.

Figure 4 is a sectional view taken on the line 4—4 of Figure 1 and looking in the direction of the arrows.

I claim:

The ornamental design for a drafting implement, as shown.

JOSEPH I. CARR.
